UNITED STATES PATENT OFFICE.

HENRY R. DE BERRY AND RAYMOND H. NEFF, OF PITTSBURGH, PENNSYLVANIA.

SPARK-ARRESTER.

1,158,989.

Specification of Letters Patent. Patented Nov. 2, 1915.

Application filed May 8, 1915. Serial No. 26,759.

To all whom it may concern:

Be it known that we, HENRY R. DE BERRY and RAYMOND H. NEFF, both citizens of the United States, residing at Pittsburgh, in the county of Allegheny and State of Pennsylvania, have invented certain new and useful Improvements in Spark-Arresters, of which the following is a specification.

The present invention relates to certain new and useful improvements in spark and cinder arresters, and has for its object to provide a device of this character which embodies novel features of construction whereby it can readily be applied as an attachment to the smoke stack of a locomotive, and will operate in an effective manner to prevent the escape of live sparks and cinders.

Further objects of the invention are to provide a spark and cinder arrester which is comparatively simple and inexpensive in its construction, which will not interfere with the draft of the boiler, which can be easily kept in perfect repair, and which can be fitted upon an ordinary locomotive without necessitating any changing or remodeling thereof.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a vertical sectional view through the smoke stack of a locomotive provided with a spark and cinder arrester constructed in accordance with the invention. Fig. 2 is a side elevation of the upper portion of the smoke stack, with the spark and cinder arrester applied thereto. Fig. 3 is an enlarged transverse sectional view through one side of the upper end of the spark and cinder arrester, showing the manner of attaching the tubular screen member at its upper end. Fig. 4 is a detail sectional view showing the manner of attaching the tubular screen member at its lower end.

Corresponding and like parts are referred to in the following description and indicated in all the views of the drawings by the same reference characters.

The spark and cinder arrester is especially designed to be applied as an attachment to

the conventional construction of locomotives without necessitating any remodeling or reconstruction thereof.

Referring to the drawings, the numeral 1 designates the boiler of a locomotive, the numeral 2 the smoke stack thereof, and the numeral 3 the steam exhaust. Surrounding the upper end of the smoke stack 2 and spaced therefrom so as to provide an annular cinder receiving chamber 4, is a shell 5, the upper edge of the shell projecting slightly above the top of the smoke stack 2, and being curved inwardly as indicated at 5^a. The lower edge of the shell 5 terminates in an inwardly extending flange 6 which extends inwardly into engagement with the exterior of the stack 2 so as to provide a bottom for the cinder receiving chamber 4, said bottom being inclined rearwardly and downwardly so as to discharge into a cinder conduit 7 which may carry the cinders to the ash pit or deposit them at one side of the track. By reference to Fig. 2, it will be observed that the exterior shell 5 is, in effect, cut off on a plane inclined at an angle to the axis thereof, the bottom flange 6 being located in the same plane and being correspondingly inclined so that the ashes and cinders collecting in the chamber 4 are discharged into the cinder conduit 7.

For the purpose of clamping the shell 5 in position upon the exterior of the stack 2, an upper clamping band 8 and a lower clamping band 9 are provided, said bands having the ends thereof extended outwardly at 8^a and 9^a respectively and connected by the respective clamping bolts 8^b and 9^b. The split portions of the clamping bands 8 and 9 are located at the front of the stack 2 and under the inclined bottom flange 6 of the shell 5 so that access can be readily had thereto. The portions of the clamping bands 8 and 9 positioned within the shell 5 are connected thereto by the pins or bolts 10 which pass radially through the cinder receiving chamber 4. When these clamping bands are loosened the shell can be bodily removed from the smoke stack, although when the clamping bands are placed in position and the clamping screws tightened the shell 5 is retained securely in proper position upon the stack.

Projecting inwardly from the upper edge of the shell 5 so as to overhang the stack 2 is a series of radially disposed and curved arms 11, the extremities of the arms being

secured to a horizontally disposed ring 12 which is arranged over and slightly spaced from the top of the stack. Suitable fastening members such as the rivets 13 may be provided for securing the arms 11 to the shell 5 and the inwardly extended beveled upper edge 5^a thereof.

Arranged within the stack 2 and extending longitudinally through the same is a tubular screen member 14, said screen member being uniformly tapered toward the lower end thereof and being arranged axially within the stack 2, the lower end of the tubular screen being secured to the steam exhaust 3, while the upper end thereof is flared outwardly over the ring 12 and arms 11. The tubular screen member 14 may be constructed in any suitable manner so that the ordinary gases of combustion will pass freely through the same while cinders and solid particles will be deflected to one side. As shown upon the drawing the tubular screen member includes an outer fine screen 14^a, and an inner coarse screen 14^b which is formed of heavy wire and serves to strengthen and reinforce the fine screen 14^a so that the latter will retain its shape.

The lower and reduced end of the tapered screen member 14 is applied to the upper end of the steam exhaust 3 of the locomotive. The lower edge of the screen member is returned upwardly and inwardly, as indicated at 14^c, around a ring 15 which is of a sufficient size to drop freely over the flanged upper end of the steam exhaust 2. A split clamping band 16 is applied to the screen member 14 immediately above the ring 15, as indicated by Fig. 4, and by tightening the clamping bolt 16^a the ring 16 can be contracted so as to draw the screen around the steam exhaust 3 immediately below the flanged end thereof, thereby securely connecting the screen member to the steam exhaust.

The flared upper end of the screen member 14 has the extreme edge thereof returned at 14^d around a ring 17 which is of a sufficient size to rest upon and engage the inwardly extending beveled upper end 5^a of the shell 5. A retaining ring 18 stamped from sheet metal or similar material is applied to the flared upper end of the screen member 14 and arranged to engage the same within the immediate confines of the ring 17. Clamping bolts 19 connect the retaining plate 18 to the beveled upper edge 5^a of the shell 5, said bolts also passing through the returned edge 14^d of the screen member. When the clamping bolts 19 are tightened the flared upper end of the tubular screen member will be securely clamped to the upper edge of the shell 5 so as to produce a tight joint between the members and hold the screen securely in position. The screen itself can be readily removed and replaced

by removing the clamping band 16 and the retaining ring 18, while the shell 5 can be bodily removed from the stack by releasing the clamping bands 8 and 9.

In the operation of the device the ordinary gaseous products of combustion pass freely through the tubular screen member 14 so as to be discharged from the upper end of the smoke stack in the usual manner, while the cinders and solid particles are engaged by the fine screen 14^a and deflected outwardly by the inclined sides thereof. The draft is sufficient to carry the cinders and solid particles to the top of the stack where they radiate outwardly and drop into the cinder collecting chamber 4. As previously explained, from this cinder collecting chamber 4 they are discharged into the cinder conduit 7.

Having thus described the invention, what we claim as new and desire to secure by Letters Patent, is:

1. A spark and cinder arrester for locomotives, including an exterior shell adapted to be applied to the top of the smoke stack so as to provide an annular cinder receiving chamber surrounding the same, arms projecting inwardly from the upper edge of the shell, a ring arranged over the top of the stack and supported by the arms, a tubular screen member extending longitudinally through the stack and having the upper end thereof flared so as to extend outwardly over the ring, means for attaching the lower end of the tubular screen member to the steam exhaust, and means for attaching the upper end of the tubular screen member to the upper edge of the shell.

2. A spark and cinder arrester for locomotives, including an exterior shell applied to the top of the smoke stack so as to provide an annular cinder receiving chamber surrounding the stack, the upper edge of the shell terminating in an inwardly extending flange, arms projecting inwardly from the upper edge of the shell, a ring arranged over the top of the stack and supported by the arms, a tubular screen extending longitudinally through the stack and having the upper end thereof flared so as to extend outwardly over the ring, clamping means for attaching the lower end of the tubular screen member to the steam exhaust, and a retaining ring clamping the flared upper end of the tubular screen against the inwardly extended flange at the upper edge of the shell.

3. A spark and cinder arrester including an annular shell applied to the exterior of the smoke stack so as to provide a cinder receiving chamber surrounding the upper end of the stack, the upper edge of the shell terminating in an inwardly extending flange, arms extending inwardly from the upper edge of the shell, a horizontally dis-

- posed ring arranged over the top of the stack and supported by the said arms, a tubular screen extending longitudinally through the stack and having opposite ends thereof returned, rings fitted within the returned ends of the tubular screen, a clamping band attaching the lower end of the screen to the steam exhaust, and a retaining ring for clamping the upper edge of the tubular screen against the inwardly extending flange at the top of the before mentioned annular shell.
4. A spark and cinder arrester for locomotives, including an exterior shell applied to the top of the smoke stack so as to provide an annular cinder receiving chamber at the upper end of the stack, arms projecting inwardly from the upper edge of the shell, a horizontally disposed ring arranged over the top of the stack and supported by the arms, a tubular screen extending longitudinally through the stack and having the upper end thereof flared so as to extend outwardly over the before mentioned arms, means for attaching the lower end of the tubular screen to the steam exhaust, and means for connecting the flared upper end of the tubular screen to the upper edge of the exterior shell.
5. A spark and cinder arrester for locomotives, including an exterior shell applied to the top of the smoke stack so as to provide an annular cinder receiving chamber surrounding the upper end thereof, the upper edge of the shell terminating in an inwardly extending flange, arms projecting inwardly from the upper edge of the shell, a horizontally disposed ring arranged over the top of the stack and supported by the said arms, a tubular screen member extending longitudinally through the stack and formed with a fine screen and a heavy reinforcing screen, the portion of the screen member within the stack being uniformly tapered toward the lower end thereof, while the upper end of the screen member is flared so as to extend outwardly over the before mentioned arms, a clamping band for attaching the tapered lower end of the screen member to the steam exhaust, and a clamping band for attaching the flared upper end of the screen member to the flange at the upper end of the shell.
6. A spark and cinder arrester for locomotives, including an exterior shell applied to the top of the smoke stack so as to provide an annular cinder receiving chamber surrounding the same, the lower end of the shell being cut off at an angle while the upper end of the shell extends slightly above the top of the stack and terminates in an inwardly extending flange, a clamping band applied to the stack and extending through the inclined bottom of the shell so as to be arranged partially within the shell and partially under the bottom thereof, arms projecting from the clamping band and engaging the shell to support the same, a second set of arms projecting inwardly from the upper edge of the shell, a horizontally disposed ring arranged over the top of the stack and supported by the second set of arms, a tubular screen member extending longitudinally through the stack and having the upper end thereof flared, means for attaching the lower end of the tubular screen member to the steam exhaust, and a retaining ring for clamping the flared upper end of the tubular screen member against the flange at the upper edge of the shell.

In testimony whereof I affix my signature in presence of two witnesses.
